William H. Stevens Inventor
By his Attorney
Grant & Kent

UNITED STATES PATENT OFFICE.

WILLIAM H. STEVENS, OF NEW YORK, N. Y.

GARTER.

Original application filed July 17, 1917, Serial No. 180,990. Divided and this application filed September 26, 1918. Serial No. 255,782.

To all whom it may concern:

Be it known that I, WILLIAM H. STEVENS, a subject of the King of Great Britain, residing at New York, in the county of New York and State of New York, have invented certain new and useful Improvements in Garters, of which the following is a specification.

This application is a divisional of my application Serial No. 180,990 filed July 17th, 1917.

The invention relates to improvements in garters and one of the objects is to provide a one-piece attaching member for garters of such construction that it will securely hold the fabric of the stocking or garment and without danger of tearing, while at the same time it is easily applied to and disengaged from the garment or stocking.

Still another object is to provide an attaching member with an attaching portion whereby it may be secured to the end of the garter fabric without stitching or other positive connecting means.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawing, which is to be taken as part of this specification, and in which I have shown merely a preferred form of embodiment of the invention, Figure 1 is an elevation of the end portion of a garter provided with a form of attaching member embodying my invention; Figure 2 is a similar view illustrating a modified form of attaching member; Figure 3 is a view of a further modified form of attaching member showing it as applied in use; Figure 4 is a perspective view of the attaching member shown in Figure 1; Figure 5 is a view similar to Figure 4 of the attaching member shown in Figure 2; Figure 6 is a view similar to Figures 4 and 5 of the attaching member shown in Figure 3; Figure 7 is a perspective view illustrating a modification of the attaching member shown in Figure 6; and Figure 8 is a perspective view of another modification.

Referring to the numerals on the drawing, there is shown at 9 a length of garter fabric, at the end of which is secured an attaching member. Referring to the attaching member shown in Figure 1, this comprises a flat frame, having an extensive cut-out portion 10, diminishing into a re-curved slot 11. Preferably the cut-out portion 10 is at the upper end of the frame and the re-curved slot 11 is symmetrically disposed at the lower end of the frame. The upper end of the frame is defined by a crossbar 12, around which the fabric 9 may be looped. Between the cut-out portion 10 and the re-curved slot 11 there is defined a tongue 14, which is resilient, because the material of which the frame is made is sufficiently thin. Between this tongue and the adjacent edge of the frame defining the slot 11, the material of the garment or stocking will be securely held. In use a bight of the material is pulled through the large opening 10, and then pushed down into the slot 11, in which slot it disposes itself evenly, avoiding undesirable bunching (see Figure 1). The construction of Figures 2 and 5 is similar to that of Figures 1 and 4, except that the crossbar 12 is provided with a pair of parallel slots 15, through which the garter fabric may be passed and in which it may be held without sewing or other positive fastening.

In Figures 3 and 6 there is a construction similar to that of Figures 4 and 5, except that the cut-out portion 10, which is symmetrically disposed medially of the upper end of the frame, diminishes into a vertical slot 16, which slot 16 in turn branches into transverse slots 17. Thus there are defined on opposite sides of the vertical slot 16 two tongues 18, both resilient. As will be noted in Figs. 6 and 7 the tongues 18 are normally flexed beyond the plane of the frame, in which position they provide a relatively wide slot 16 to permit easy insertion of the fabric, but upon the pulling strains exerted upon the tongues 18 by the fabric, these tongues 18 approach the plane of the frame and firmly pinch the fabric therebetween. In the use of this form of the device the material is introduced through the cut-out portion 10, then forced down through the slot 16 and thence parts of the material into the slot 17 where the material distributes itself and is held.

The form of device shown in Figure 7 is similar to that of Figure 6, except that the crossbar 12 is provided with slots 15 as and for the purpose described with reference 5 to the same construction shown in Figure 5.

In Figure 8 there is a frame provided with a cut-out portion 10 like that of Figure 6 diminishing into a vertical slot 16, but there are no transverse branches.

10. The tongue 14 as shown in Figs. 1, 2, 4 and 5 is gradually flexed to one side of the frame so that the free end of the tongue is slightly spaced from the slotted opening in the frame. By doing this it is not necessary to initially flex the tongue, as in the known art, 15 to one side of the frame to permit insertion of a portion of the goods to be supported.

Inasmuch as many changes could be made in the above construction, and many apparently widely different embodiments of my invention could be made without departing from the scope thereof, it is intended that all matter contained in the above description or shown in the accompanying drawing 25 shall be interpreted as illustrative and not in a limiting sense.

It is also to be understood that the language used in the following claims is intended to cover all the generic and specific 30 features of the invention herein described and all statements of the scope of the invention which, as a matter of language, might be said to fall therebetween.

I claim:

35. 1. A garment supporter comprising a substantially flat open centered frame, a gripping tongue resiliently connected to said frame and substantially filling the opening therein, the free end of said tongue being

normally flexed beyond the plane of the 40 frame.

2. A garment supporter comprising a substantially flat open centered frame, a gripping tongue resiliently connected with one side wall of the frame and extending substantially to the opposite side wall of the frame, the free end of said tongue being 45 normally flexed beyond the plane of the frame.

3. A garment supporter comprising a flat 50 frame having a cut-out portion and a tongue resiliently connected to the frame and projecting downwardly and inwardly into the cut-out portion, the free end of said tongue being normally flexed beyond the plane of 55 the frame.

4. A garment supporter comprising a flat frame having a tapering cut-out portion 60 therein diminishing into a re-curved slot, the portion of the frame intermediate the cut-out portion and the re-curved slot defining a resilient tongue, the free end of said tongue being normally flexed beyond the plane of the frame.

5. A garment supporter comprising a flat 65 frame having a relatively large opening therein, a tongue resiliently connected to the side wall of the frame and projecting inwardly and downwardly into the opening 70 in the frame, the free end of said tongue being normally flexed beyond the plane of the frame and adapted to coact with the bottom wall and lower portions of the side walls of the opening to constitute a grip for 75 the garment.

In testimony whereof I affix my signature.

WILLIAM H. STEVENS.
